UNITED STATES PATENT OFFICE.

ADOLPH MUCHLMATT, OF NEWPORT, KENTUCKY.

TOOL-SHARPENER.

974,907.

Specification of Letters Patent.

Patented Nov. 8, 1910.

Application filed June 30, 1909. Serial No. 505,178.

To all whom it may concern:

Be it known that I, ADOLPH MUCHLMATT, a citizen of the United States of America, and resident of No. 807 Maple avenue, New-
5 port, county of Campbell, and State of Ken-
tucky (post-office address, Fifth and Elm
streets, in the city of Cincinnati, county of
Hamilton, and State of Ohio), have invented
10 an Improvement in Tool-Sharpener; and I
do hereby declare the following to be a full
and exact description thereof, reference being
had to the accompanying drawings, making
part of this specification.

My invention relates to tool sharpeners
15 and it has for its object the improvement in
the construction of such devices whereby
they are simplified and rendered more effi-
cient.

The novelty of my invention consists in
20 the combination and sub-combination of the
parts as will be hereinafter set forth and
specifically pointed out in the claim.

In the drawings: Figure #1, is a view of
25 my tool sharpener when it is used for facing
a tool. Fig. #2, is a view of my tool sharp-
ener when it is used for sharpening a tool.
Fig. #3, shows the tool sharpener in pos-
30 sition for either lapping or facing a punch.
Fig. #4, is a vertical longitudinal section
when the verniers are at zero. Fig. #5, is a
vertical section through one foot showing
ball bearing cage.

Similar letters of reference indicate corre-
35 sponding parts.

Referring to the drawings A represents a
base on which the stone and tool grinder are
placed when in operation. When facing a
40 tool, the stone B is placed on edge on the
base as shown in Fig. #1. When doing any
ordinary grinding the stone B, is placed flat
as shown in Fig. #2 and #3. The face A²
45 of the base is made perfectly true and par-
allel with the face of the stone. The main
frame of the tool holder C has two feet C²
50 in which are placed ball bearings C³, C³.
Through the main frame C passes a vertical
threaded standard D. The portion of the
main frame through which the standard D
55 passes has a slot C⁴ in which is placed a nut
D² which is used for lowering and raising
the standard D. The upper end of the stand-
ard D has a lock nut D³ for locking the
standard in any position desired. The
threaded portion of the standard D has a
55 slot or key way D⁴ cut in it in which plays a

pin D⁵. This pin is to prevent the standard
D from turning when the nut D² is turned
for raising or lowering the standard. The
upper end of the standard has a head D⁶,
through which passes a horizontal hole D⁷.
In this hole D⁷ plays a spindle E which is a
part of the horizontal arm E². The outer
end of the spindle E is threaded and has a
lock nut E³. On the opposite side of the head
D⁶ from the lock nut E³ is a revolving thim-
ble E⁴. This thimble is graduated in degrees
and marks or zero points are placed on the
head D⁶ and that portion of the arm E² that
comes in contact with the thimble E⁴ so that
the arm E² can be set at any angle to the
head D⁶ desired. In the outer end of the
arm E² there is a head F. The outer end of
the arm E² has a vertical hole E⁵ in which a
spindle F² plays. On the upper end of the
spindle F² there is a lock nut F³. On the
lower side of the spindle F², next to the arm
there is a graduated thimble F⁴, which is
graduated in degrees so that the head F, can
be set to any angle desired. The extreme
lower part of the head F has a sliding piece
F⁵, which is operated by a screw F⁶. The
screw when screwed in forces the sliding
piece F⁵ toward the two studs F⁷. When the
screw F⁶ is backed out, the spring F⁸ forces
the sliding piece F⁵ back, following the screw
F⁶ as it is backed out.

The operation of my tool grinder is as fol-
lows: The tool to be ground is placed in the
head E and securely clamped by the screw
F⁶. Then the head F and the arm E² are
adjusted to the desired angles, the threaded
standard D raised to the height that is suited
for the work to be done when the ball bear-
ings, C³, C³ are placed on the face A² and
slid back and forward, the tool at the same
time coming in contact with the stone B,
when the tool will be ground to what ever
angle it may be set for.

Having described my invention what I
claim is,

The combination in a tool sharpener of a
main frame, a vertical threaded standard, a
horizontal arm, with a head for holding the
tool, the head having a sliding piece oper-
ated by a screw and spring, with two sta-
tionary studs, all substantially as described.

ADOLPH MUCHLMATT.

Witnesses:

D. C. KELLER,
E. LEMON.

It is hereby certified that in Letters Patent No. 974,907, granted November 8, 1910, for an improvement in "Tool-Sharpener," an error appears requiring correction as follows: In the grant, in the printed specification, and in the headings to the drawings, the name of the applicant was erroneously written and printed "Adolph Muchlmatt," whereas said name should have been written and printed *Adolph Muchlmatt*; and that the said Letters Patent should be read with this correction therein that the same may conform to the record of the case in the Patent Office.

Signed and sealed this 17th day of January, A. D., 1911.

[SEAL.]

C. C. BILLINGS,

Acting Commissioner of Patents.
